UNITED STATES PATENT OFFICE.

MAX F. DE BAJLIGETHY, OF HOUSTON, TEXAS.

STILL.

Application filed June 20, 1922. Serial No. 569,614.

To all whom it may concern:

Be it known that I, MAX F. DE BAJLIGETHY, citizen of the United States, residing at Houston, in the county of Harris and 5 State of Texas, have invented certain new and useful Improvement in a Still, of which the following is a specification.

This invention relates to new and useful improvements in a still.

10 One object of the invention is to provide a still specially designed for use in the distillation of hydrocarbon, and whereby the elements of high gravity may be separated from the heavier elements.

15 Another object of the invention is to provide a still of the character described having a drum located within the boiler and through which the petroleum or other hydrocarbon to be distilled passes before it enters

20 the boiler, said drum being provided for the purpose of collecting sediments and other heavy elements to prevent their being deposited in the bottom of the boiler. Without this drum the heavy elements and solid

25 matter in the fluid would settle on the bottom of the boiler forming a thick heat retaining coat which would soon cause the bottom of the boiler to be burned out, with the result that the contents of the boiler

30 would be suddenly discharged into the furnace causing an explosion. To prevent this the drum has been provided.

Another object of the invention is to provide a still of the character described provided with a drum within the boiler through which the hydrocarbon passes before being discharged directly into the boiler, said drum being provided for the further purpose of relieving the boiler of an excessive 40 amount of pressure.

A still further feature of the invention resides in the provision of a still so constructed that the petroleum or other hydrocarbon to be distilled is discharged into the bottom of the boiler through a nozzle so located that there will be a constant current or wave of fluid passing along the bottom of the boiler and keeping said bottom cleansed of settling or sediment which would otherwise tend to collect on and adhere to the bottom.

With the above and other objects in view the invention has particular relation to certain novel features of construction, operation and arrangement of parts, an example of which is given in this specification and

illustrated in the accompanying drawings, wherein:—

Figure 1 shows a vertical sectional view 60 of the still.

Figure 2 shows a transverse sectional view taken on the line 2—2 of Figure 1.

Figure 3 is an end view of the boiler and,

Figure 4 is a transverse sectional view of one of the domes employed taken on the line 65 4—4 of Figure 2.

In the drawings, the numeral 1 designates the boiler, under which there is a furnace 2. The boiler is filled with hydrocarbon through an inlet line 3. This line is formed 70 into a coil 4 within the furnace and is controlled by a back pressure valve 5. It enters the end of the boiler near the top and within said boiler branches and enters the drums 6, 6, one end of each of which projects out through the opposite end of the boiler and are securely anchored to said end. Leading from the last mentioned ends of the drums there is an outlet pipe 8 which turns 75 downwardly and inwardly forming a nozzle 9, which enters the adjacent end of the boiler near the bottom thereof and which is controlled by a gate valve 10.

The boiler 1, at each end is formed with 80 vertical cylindrical domes, 11, 11. These domes have the central flues 12, 12 which are fastened at their upper ends to the top of the domes, and have inlet openings 13, 13. The flues 12 are controlled by a suitable gate 85 valve as 14 located near their upper ends. The flues depend into the boiler, and their lower ends are connected by a connecting pipe 15, leading from which to the central dome 16 of the boiler there is a pipe 17. A line 18 leading from the dome 16 enters a 90 suitable condenser (not shown).

Within the domes 11 there are the disc-like inverted conical shaped baffles 19 spaced apart. These baffles are anchored at their outer edges to the domes 11 and at their inner edges to the flues 12 and opposite each baffle there is secured around each dome the annular plates 20. These plates radiate the heat and keep the baffles 19 comparatively 100 cool. The fluid in the boiler is kept at a high degree of temperature and the lighter elements are constantly being given off and passed up through the baffles 19, which are perforated, and enter the upper ends of the flues 12 and then pass downwardly through 105 said flues, and through the pipes 15 and 17 into the dome 16 and thence out through the 110

line 18 into the condenser. The heavier particles are arrested by the baffles 19 and drop back into the boiler to be again broken up by the heat therein, the lighter elements 5 constantly passing up through the domes 11 and the heavier elements being arrested and dropping back into the boiler. A very high percentage of the hydrocarbon in the boiler is thus distilled and the lighter elements 10 are extracted therefrom.

As hereinbefore indicated the fluid, before entering the boiler proper, passes through the drums 6. These drums are of considerable capacity and the fluid contained therein is given an opportunity to settle, the solid particles and refuse settling to the bottom of the drums. The exposed end of each drum has a removable head 21 permitting the cleansing of the drums at proper 15 times. A high percentage of this solid matter is thus collected from the fluid before it enters the boiler so that there will be only a small amount of sediment retained in the fluid entering the boiler proper, and the discharge of the fluid 20 through the nozzle 9 along the bottom of the boiler will prevent this from settling and adhering to the bottom of the boiler, thus protecting said bottom from the liability of 25 burning out.

What I claim is:—

1. The combination with a still including a boiler, of a plurality of reacting drums mounted therein, and one end of which pro-

jects outside of the boiler, a detachable head 35 carried by the outer ends of said drums, an inlet pipe formed with heating coils entering one end of the drum and a discharge nozzle leading from the outer end of the drum and entering the boiler.

2. In combination a still including a boiler, a reacting drum anchored therein, one end of which projects out of said boiler, a detachable head carried by said end, a heating coil, an inlet line leading from said coil and entering said drum, a back pressure valve controlling said line, a discharge line leading from the drum and terminating in a nozzle within the boiler, through which the contents of the drum may be discharged 40 into the boiler, and a valve for regulating the flow or fluid through the discharge line.

3. In combination a still including a boiler, a reacting drum within said boiler, one end of which projects out beyond the boiler 45 end, and is provided with a detachable head and is anchored to said end, a heater coil, an inlet line leading from said coil and entering said drum, a discharge nozzle leading from the projecting end of said drum, and terminating in a nozzle which enters the boiler through which the contents of the drum may be discharged into the bottom of the boiler and valves controlling said lines.

In testimony whereof I have signed my 55 name to this specification.

MAX F. DE BAJLIGETHY.
